FLATIRON HANDLE

James L. Terrell, 1020 Broadway St.,
North Chicago, Ill. 60064

Filed Mar. 5, 1969, Ser. No. 16,317

Term of patent 14 years

Int. Cl. D7—06

U.S. Cl. D49—6

FIG. 1

FIG. 4

FIG. 2

FIG. 3

FIG. 1 is a side elevation view of a flatiron handle showing my new design;

FIG. 2 is a perspective view thereof.

FIG. 3 is an elevation view taken from the front end thereof;

FIG. 4 is an elevation view taken from the end opposite that shown in FIG. 3.

The dominant features of my design reside in the portions shown in full lines, it being understood that the broken line representations of the flatiron base are for purposes of illustration only.

The broken line representations of the flatiron base, the control knob and the cord are for illustrative purposes only and form no part of the claim.

What I claim is:

The ornamental design for a flatiron handle, as shown and described.
